UNITED STATES PATENT OFFICE

154,446

DESIGN FOR A HOUSEHOLD WEIGHING
SCALE

Charles T. Walter, Harvey, Ill.

Application July 9, 1947, Serial No. 140,166

Term of patent 7 years

(Cl. D52—10)

To all whom it may concern:

Be it known that I, Charles T. Walter, a citizen of the United States, residing at Harvey, in the county of Cook and State of Illinois, have invented a new, original, and ornamental Design for a Household Weighing Scale, of which the following is a specification, reference being had to the accompanying drawing, forming a part thereof.

Figure 1 is a perspective view of a household weighing scale looking diagonally downwardly thereon, showing my new design.

Figure 2 is a front elevational view; and

Figure 3 is a plan view of the scale.

I claim:

The ornamental design for a household weighing scale, as shown.

CHARLES T. WALTER.
